UNITED STATES PATENT OFFICE.

WILLIAM K. EDGAR, OF COLORADO SPRINGS, COLORADO.

SEAL-LOCK.

SPECIFICATION forming part of Letters Patent No. 605,278, dated June 7, 1898.

Application filed June 9, 1897. Serial No. 640,013. (No model.)

To all whom it may concern:

Be it known that I, WILLIAM K. EDGAR, a citizen of the United States, residing at Colorado Springs, in the county of El Paso and State of Colorado, have invented a new and useful Seal-Lock, of which the following is a specification.

The invention relates to seal-locks, and particularly to seals for use in connection with lock constructions such as or similar to those shown in the patent granted to myself and W. L. Sebring, No. 563,916, on July 14, 1896, and the patent granted to me, No. 584,544, on June 15, 1897, wherein the seal is engaged and held in place by means of a locking-pin disposed to operate perpendicular to the plane of the seal and performing the additional function of securing the locking-bolt in its extended or operative position, said locking-pin engaging the seal from the rear and preferably projecting through an opening in the seal to lie at its front end in or contiguous to the plane of the front surface of the seal and hence visible to the official whose duty it is to inspect the locks to indicate whether or not the seal is properly secured in place.

The object of the present invention is to provide a simple and efficient construction of frangible seal adapted to be engaged by a locking-pin approaching the same from its rear side and having an opening through which the front end of the locking-pin is adapted to project.

A further object of the invention is to provide a seal wherein the opening for the reception of the front end of the locking-pin is of larger diameter than the locking-pin to prevent the dishonest substitution for the locking-pin of a false locking-pin end or plug constructed to resemble the front end of a locking-pin and arranged in the seal to mislead those officials whose duty it is to inspect and inquire into the correct locking of cars or similar receptacles with which the locks are equipped. If the opening in the seal through which the extremity of a locking-pin projects from the rear is of equal or approximately equal size with the locking-pin, it is possible by inserting a false locking-pin end or plug into the opening of the seal to introduce the seal into its proper place or seal-seat in the lock, while the locking-pin proper remains

in its repressed or inoperative position, said seal being temporarily fastened in place by readily-detachable means known to accomplishes of those who have wilfully inserted the plugged seal. With this arrangement the only operation necessary to gain access to the car or receptacle provided with the lock is to remove the means employed for temporarily securing the seal in its place, dismount the seal intact, and operate the lock; but by employing an opening in the seal which is of larger diameter than the extremity of the locking-pin the introduction of a plug of suitable size to fill the opening would be too large to be mistaken for the end of the locking-pin, and, furthermore, any plugging of the opening in the seal which would prevent a view of the contiguous interior of the seal-lock would be apparent to inspectors inquiring into the correctness of the operation of locking.

Further objects and advantages of this invention will appear in the following description, and the novel features thereof will be particularly pointed out in the appended claims.

In the drawings, Figure 1 is a perspective view of a seal-lock, showing in operative position a seal constructed in accordance with the invention. Fig. 2 is a vertical central section of the same. Fig. 3 is a detail view of the seal detached. Fig. 4 is a vertical section of a portion of the lock, showing a modified construction of seal wherein the opening is of a size to snugly fit the end of the locking-pin. Fig. 5 is a similar view showing the opening in a seal-plug in front of the repressed locking-pin and secured in place by means other than those provided for use in the legitimate operation of the device, as when car-door locks are manipulated through collusion between or with railroad employees.

Similar numerals of reference indicate corresponding parts in all the figures of the drawings.

The lock in connection with which the seal 1 is employed includes a seal-seat 2, provided at its top and sides with overhanging flanges 3 and being accessible for the introduction of the seal at one side only—namely, in the construction illustrated at its lower side—and a bolt 4, which is longitudinally slotted, as at

5, to receive the reduced portion or neck 6 of a locking-pin 7, mounted for movement perpendicular to the plane of the seal-seat and also perpendicular to the bolt, said bolt being adapted to engage a staple 9, and thereby secure a hasp 10. The locking devices for the locking-pin are concealed in a rearward extension or mortised portion 11 of the lock-casing, whereby said locking devices are 10 accessible from the front of the lock to prevent tampering; but as said locking devices are similar to those shown particularly in said former patent, No. 584,544, granted June 15, 1897, any specific description thereof is unnecessary, except in so far as it is desirable to state that they include a releasing-pin 12, which projects forward parallel with the locking-pin and terminates in a cavity 13 in rear of the plane of the seal-seat, where it is fitted 15 with a pivotal handle or ring 14, adapted to lie in rear of the plane of the seal and at one point between the locking-pin and that side of the seal-seat which is opposite to its open side or opposite to that side through which 20 the seal is introduced.

It will be seen that in so far as the construction of the lock is concerned the locking-pin secures both the bolt and the seal in their normal or operative positions and is itself secured 25 by locking devices connected with a releasing pin or trip which projects forward to a point contiguous to the plane of the rear side of the seal and is protected or guarded against tampering by the seal.

30 The seal, which is preferably made of clay or similar frangible material, is provided at a suitable point in alignment with the locking-pin with an opening 15, through which the front end of the locking-pin is adapted 35 to extend when in its normal position, whereby after the extension of the locking-pin the seal may not be removed from its seat except it be destroyed, even the breaking of the seal in half not allowing the removal of any portion thereof except that which is between the locking-pin and the open side of the seat. The removal of said outer portion of the seal will not allow the inner portion, or that which is located between the locking-pin and that 40 side of the seat which is opposite to its open side, to be displaced.

In Fig. 4 I have shown a seal in which the opening is of a size approximately equal to that of the front end of the locking-pin; but 45 while the object in allowing the front end of the locking-pin to project forward through the opening in the seal to the front face thereof is to enable an inspector to see that the locking-pin is properly in engagement with 50 the seal I am aware that it is possible when the opening in the seal is of equal size with the locking-pin to tamper with the lock through collusion with railroad employees. For instance, a false locking-pin end or plug 55 16 (see Fig. 5) may be secured in the opening in the seal and the latter placed in its seat without advancing the locking-pin, and hence

without making use of the locking devices provided for securing said pin in its normal or operative position. The seal may be secured 70 temporarily in its proper position by means of a small plug or wedge 17 introduced between the lower edge of the seal and the contiguous surface of the casing, as may be seen by reference to Fig. 5. With this arrangement when the proper time comes for 75 opening the car by the accomplices of the person who has improperly sealed the cars all that is necessary is to withdraw the wedge 17, remove the seal, and open the lock, which 80 obviously has not been properly locked, and which was only made to appear for the purposes of inspection to be properly locked. When it is desired to restore the parts to their proper positions after the car or receptacle 85 has been rifled, the seal may be returned and the locking-pin properly engaged therewith, the false plug having previously been removed from the opening of the seal.

In order to guard against tampering with 90 the lock in the manner above indicated, the preferred form of seal is made with an opening which in size is in excess of that necessary for the reception of the locking-pin, whereby the contiguous portions of the sides of the 95 locking-pin are exposed therethrough and whereby any attempt to plug the opening would be readily discernible, for the reason that a plug of the size necessary to fill the enlarged opening would be too large to mislead 100 any one intrusted with the inspection of the locks. By reason of the locking devices for the locking-pin being located in the mortised extension of the lock-casing, and hence a considerable distance in rear of the plane of the 105 bolt and seal-seat, the enlargement of the opening in the seal does not operate to impair the efficiency of the lock. The opening may be made of sufficient size, as indicated in the drawings, to expose a portion of the ring or 110 handle and the releasing pin or trip, and thereby show to the inspector that said parts are in their proper positions, without in any way affecting the security of the device, for the reason that the releasing pin or trip cannot 115 be advanced to disengage the locking devices without first releasing the handle by which it is held depressed, and said handle cannot be released except by removing every portion of the seal from its seat. If the seal 120 is broken sufficiently to remove the entire lower portion thereof, as indicated by the broken dotted line α of Fig. 1, and thus wholly expose the front end of the releasing pin or trip and more than half of the handle 125 or ring, the parts are still securely locked and will remain so until the remaining portion of the seal, which is arranged between the locking-pin and that side of the seat which is opposite to its open side, has been removed, this 130 removal being possible of accomplishment only by breaking and thus destroying said upper or inner portion of the seal.

Hence by making an enlarged opening in

the seal—and by "enlarged" is meant an appreciable increase of size whereby the opening fits loosely on the extremity of the locking-pin—the introduction of a false locking-pin end could be readily detected by its difference in size from the proper locking-pin, and therefore the contiguous portions of the lock in rear of the plane of the seal are exposed through the opening when the parts are properly engaged.

An important advantage of the construction of lock and seal set forth in the foregoing specification is that the described relative arrangement of parts provides for a certain looseness of fit without in any way reducing the security of the fastening, and hence enables the metal parts of the device to be manufactured wholly of castings and enables the manufacturer to dispense with machine-work, thereby reducing the cost, and hence the use of a large opening in the seal has an important advantage in addition to those hereinbefore mentioned, this advantage consisting in the fact that the area of the opening allows a certain latitude for irregularities in the manufacture of the lock and enables any seal having a large opening to be introduced and secured in place without requiring the operator to search for the opening. Thus the seal may be inserted and pushed to place by one hand of the operator, and at the same time the locking-pin may be advanced by the same hand to secure the seal. No loss of time is sustained in setting the lock, and at the same time the opening in the seal may be comparatively roughly formed without interfering with the described engagement.

Various changes in the form, proportion, and the minor details of construction may be resorted to without departing from the spirit or sacrificing any of the advantages of this invention.

Having described my invention, what I claim is—

45 1. In a seal-lock, the combination with a

seal-seat and a movable member arranged in rear thereof, for advancement in a direction intersecting the plane of the same, of a seal having an opening to receive, and expose for inspection, the front end of said movable member, the opening in the seal being of greater area than the cross-section of the engaging portion of the movable member, to fit loosely on the latter and prevent the temporary fitting of a false plug, of the same cross-sectional area as the movable member, in said opening, substantially as specified. 55

2. A frangible seal having an opening extending entirely therethrough, in combination with a lock-casing having a seat into 60 which the seal may be slid, a locking-pin mounted in rear for advancement in a direction intersecting the plane of the seal, and adapted to engage and fit loosely at its front end in the opening of the seal to prevent the 65 unseating thereof, and locking devices for the locking-pin, including actuating means arranged in rear of and held inoperative by the seal, and visible through said opening in the seal between the sides of the opening and 70 the engaging pin, substantially as specified.

3. As a new article of manufacture, a frangible seal having an opening for engagement by the movable member of a lock, which opening is of greater area than the cross-section of the engaging portion of said member, to allow view through the opening, between its walls and the sides of the engaging member, and prevent fitting the opening with a false plug of the same, or approximately the 75 same, cross-sectional area as said movable member, substantially as specified. 80

In testimony that I claim the foregoing as my own I have hereto affixed my signature in the presence of two witnesses.

W. K. EDGAR.
